FUEL DEFLECTING MECHANISM

Morton F. Robertson, Chattanooga, Tenn., assignor, by mesne assignments, to The Standard Stoker Company, Inc., New York, N. Y., a corporation of Delaware

Application March 7, 1933, Serial No. 659,921

9 Claims. (Cl. 110—101)

This invention relates generally to a firebox construction and particularly to the firebox of a locomotive, the firing opening of which is provided with a fuel deflecting member above the path of the introduced fuel and fire door, and it is an object of the invention to provide an arrangement whereby the deflecting member forms a shield for the fire door against the heat of the fire in the firebox.

More specifically it is an object of the invention to provide a firebox having a firing opening with a fuel casing communicating with the lower portion of the opening, a fire door for the upper portion of the opening, a fuel deflecting member movably mounted in said opening above the path of the introduced fuel and means for actuating the fire door and the deflecting member.

It is another object of the invention to provide, in a structure of the type described, an arrangement for simultaneously opening the fire door and moving the deflecting member to a position where it will not obstruct the firing opening, and for simultaneously closing the fire door and moving the deflecting member to its operative position.

Further objects of the invention reside in the details of construction of the deflecting member, the fire door and other parts, and the novel arrangement and combination of the parts as will appear from the following description when read in conjunction with the drawings, in which

Figure 1 is a vertical longitudinal section through a portion of the rearward end of a locomotive showing the invention in elevation, with parts broken away, applied to the firebox of the locomotive;

Figure 2 is a view of the structure of Figure 1 in rear elevation; and

Figure 3 is a sectional view taken on the line 3—3 of Figure 1.

Figure 4 is a sectional view taken on the line 4—4 of Figure 1.

Figure 5 is a sectional view taken on the line 5—5—5 of Figure 2.

Throughout the description, the term "forward" is used to denote the general direction in which fuel passes through the stoker into the firebox.

According to the construction shown in the drawings, the invention is illustrated as applied to a locomotive boiler having a backwall or rear water leg 10 with a firebox opening 11 therethrough. A deck 12 extends rearwardly from the backwall 10, below the lower marginal edge of

the firebox opening 11. Suitable means is provided for discharging fuel to or into the lower portion of the firebox opening, as for example, by a stoker designated generally by the numeral 13. The stoker 13 includes a fuel casing 14 communicating with the lower portion of the firebox opening 11.

The upper portion of the firebox opening, above the casing 14, is provided with an arched door frame 15 on which is mounted a firedoor 16 comprising the door members 17 which meet upon the vertical center line of the firebox opening and are pivoted upon pins 18 to swing laterally and vertically. The door members 17 when open permit hand firing of fuel and permit the insertion of a hook or poker through the firebox opening when raking or cleaning the fire.

Suitable means is provided for scattering fuel over the fire, and in the present instance there is shown a distributor plate 19 over which fuel is projected by pressure fluid issuing from a distributor head 20 located at the rear of the distributor plate 19. In scattering fuel over the firebed in a firebox, particularly over the firebed of a locomotive firebox, a comparatively large amount of fuel particles are carried through the stack unconsumed, causing not only a very appreciable economic loss but also creating a nuisance by reason of the fact that the unconsumed particles are carried back into the coaches and deposited along the right of way. To overcome these sources of economic loss and annoyance, the use of top deflectors which tend to hold the fuel down closer to the firebed where they will be consumed, has been proposed.

These difficulties have been overcome in a large measure by the use of top deflectors in conjunction with a distributor plate. However, in some of such constructions the top deflector has interfered with the use of a hook or poker in raking or cleaning the fire. In my construction when the fire door is opened preparatory to raking or cleaning the fire, the deflecting member 21 is arranged to be automatically raised about a pivot adjacent the top outer marginal edge of the firebox to a position adjacent the upper marginal edge of the firebox opening, providing an unobstructed opening sufficiently large to permit the insertion of a hook or poker therethrough.

The fire doors 17 may be operated by a fluid pressure apparatus comprising a cylinder 22, containing a piston 23 for actuating the doors 17, and a valve casing 24, containing a valve member 25 for controlling the admission of fluid to the pipe 26, and the cylinder 22 from the line 27.

Preferably, the doors 17 and the operating mechanism therefor are constructed after the fashion of the well known "Franklin butterfly door" as shown in Patent No. 1,171,463 granted February 15, 1916, to Samuel D. Rosenfelt. The doors 17 are geared with each other by teeth in the quadrant 50 at the upper end of each door and movement of one operates the other. A link 51 is attached at one end to the upper end of the quadrant of one of the doors and engages a pin 52 at its other end. The pin 52 extends through a slot in the wall of the cylinder 22 and is mounted in the piston 53. Admission of fluid pressure to the pipe 25 causes the piston 53 to move toward the open end of the cylinder. Like movement is given to the quadrant 50 and the firedoors 17 are caused to swing open about the pins 18. The valve casing 23 is securely fastened to the valve casing 27 in a suitable manner, as by the bolts 28 passing through the flange 29 and the valve casing 27 in turn is securely fastened to the flange 30 of the stoker discharge casing 14 by suitable means, as by the bolts 31 passing through the flange 32.

Normally, the valve member 24 is seated, as shown in Figure 3, against the pressure of the fluid in the line 26 by the pressure of the spring 33. In this position no pressure fluid is admitted through the pipe 25 to the cylinder 22 and the doors 17 remain closed. When it is desired to open the doors 17 in order to rake the fire or for any other reason, the treadle 34 is depressed, which, through the arms 35 and 36, raises the valve member 24 against the pressure of the spring 33. With the valve member 24 in its raised position, pressure fluid passes from the line 26, through the pipe 25 to the cylinder 22 opening the door members 17.

At the same time that pressure fluid passes from the line 26 to the pipe 25 to open the door members 17, pressure fluid also passes through the port 37 depressing the piston 38 to its lowermost position in the casing 27. The movement of the piston 38 is transmitted to the piston rod 39 which in turn raises the deflecting member 21 to a position adjacent the upper marginal edge of the firebox opening through the link 40 and arm 41. When the fireman removes his foot from the treadle 34, the valve member 24 is lowered by the pressure of the spring 33, thereby cutting off the supply of pressure fluid to the pistons operating the door members 17 and deflecting member 21, respectively. Since the door members 17 are hinged at their upper ends and the deflecting member 21 is pivoted at its rearward end, the overhanging weight of the doors causes them to close and the overhanging weight of the deflecting member causes it to drop back into its operative position in the firing opening.

The deflecting member 21 comprises the hollow flat plate-like forward portion 42 slightly less in width than the width of the firing opening, and a hollow rearward portion 43, of lesser width than the forward portion 42, formed with the transversely extending tubular shaft 44. A pair of aligned bearings 45 and 46 are preferably formed integral with and at the opposite upper sides of the top of the firedoor arch 15. The tubular shaft 44 is in alignment with the bearings 45 and 46 and a hollow shaft 47 extends therethrough, holding the deflecting member 21 in place but permitting movement thereof about the axis of the shaft 47.

The portion of the shaft 47 adjacent the opening between the hollow rearward portion 43 and

the tubular shaft 44 of the deflecting member 21 is provided with a plurality of perforations 48 to permit the introduction of air through the hollow shaft 47 into the hollow deflecting member 21. The deflecting member 21 is provided with perforations 49 through which air is drawn into the furnace by the draft in the firebox, thus a continuous stream of cool air passes through the deflecting member, materially increasing the life thereof and providing a source of air for effecting complete combustion of the fuel in the firebox.

The deflecting member also functions as a shield for the firedoor protecting it from the intense heat of the fire and may be employed as such in furnaces arranged for stoker or manual firing of fuel.

I claim:

1. In combination with a firebox having a firing opening, a fuel casing communicating with the lower portion of said opening, means for projecting fuel forwardly therefrom into said firebox, a firedoor for the upper portion of said opening, a fuel deflecting member pivotally mounted at its rearward end and extending into said firebox and above the horizontal plane of the fuel projecting means, said fuel deflecting member being normally in a fixed position in the firing opening above the horizontal plane of the fuel projecting means, a pressure fluid operated piston for opening said fire door, a pressure fluid operated piston for raising said deflecting member about its pivotally mounted end, valvular means for simultaneously admitting pressure fluid to operate said pistons for opening said firedoor and raising said deflecting member, the closure of said valvular means permitting the simultaneous closure of said firedoor and the return of said fuel deflecting member to its lowered position.

2. In combination with a firebox having a firing opening, a fuel casing communicating with the lower portion of said opening, means for projecting fuel forwardly therefrom into said firebox, a projected fuel deflecting member above the horizontal plane of the fuel projecting means and above the path of the fuel stream pivotally mounted at its rearward end, said fuel deflecting member being normally in a fixed position in the firing opening above the horizontal plane of the fuel projecting means, a firedoor for the upper portion of said firing opening, a fluid actuated piston, connections from said piston to said door for opening the same, a second fluid actuated piston, connections from said last named piston to said deflecting member for raising the same about its pivotally mounted end, valvular means for simultaneously admitting pressure fluid to said pistons for opening said firedoor and raising said deflecting member, the closure of said valvular means permitting the simultaneous closure of said firedoor and the return of said fuel deflecting member to its lowered position.

3. In combination with a firebox having a firing opening, a fuel casing communicating with the lower portion of said opening, means for projecting fuel forwardly into said firebox in aerial paths, a fuel deflecting member above the path of the projected fuel stream arranged for movement towards and away from such path, said fuel deflecting member being normally in a fixed position in the firing opening above the horizontal plane of the fuel projecting means, a firedoor for the upper portion of said firing opening, fluid pressure actuating means for moving said deflecting member and fluid pressure actuating

- means for opening said firedoor, and valvular means for simultaneously admitting fluid to and simultaneously interrupting admission of fluid to said actuating means.
5. In combination with a firebox having a firing opening, a fuel casing communicating with the lower portion of said firing opening, a distributor plate mounted in said firing opening for receiving fuel from said fuel casing, means at the 5 rear of said plate arranged to project fuel thereover, and a hollow fuel deflecting member positioned above said distributor plate and mounted to swing upwardly about its rearward end, said deflecting member having a plurality of spaced 10 openings at its forward end, said rearward end having an atmospheric opening whereby a current of air may be admitted to said deflecting member through said open rearward end and exhausted through said spaced openings.
10. In combination with a firebox having a firing opening, a fuel casing communicating with the lower portion of said opening, means for projecting fuel forwardly into said firebox in aerial paths, and a hollow fuel deflecting member 15 pivotally mounted at its rearward end adjacent the outer upper marginal edge of said firing opening above the horizontal plane of the fuel projecting means and extending downwardly and forwardly through said opening above the 20 path of the projected fuel, said deflecting member having a plurality of spaced openings at its forward end, said rearward end having an atmospheric opening whereby a current of air may be admitted to said deflecting member through 25 said open rearward end and exhausted through said spaced openings.
30. In combination with a firebox having a firing opening, a fuel casing communicating with the lower portion of said opening, means for projecting fuel forwardly into said firebox in aerial paths, a firedoor frame embracing the upper portion of said firing opening, a firedoor mounted upon said frame, horizontal bearings formed with 35 said frame, a hollow shaft pivotally mounted in said bearings and having its ends opening to atmosphere, and a hollow fuel deflecting member above the path of the fuel on said hollow shaft, said deflecting member being provided with a 40 plurality of spaced openings and said hollow shaft being provided with a plurality of spaced openings communicating with the interior of said hollow deflecting member whereby a current of air may be admitted to said deflecting member through said hollow shaft and exhausted through 45 said spaced openings.
50. In combination with a firebox having a firing opening, a fuel casing communicating with the lower portion of said opening, means for projecting fuel forwardly into said firebox in aerial paths, a hollow fuel deflecting member above the horizontal plane of the fuel projecting means and above the path of the fuel arranged for upward swinging movement about a pivot at its rearward 55 end, said deflecting member having a plurality of spaced openings and an open rearward end

whereby a current of air may be admitted to said deflecting member through said open rearward end and exhausted through said spaced openings, a firedoor for the upper portion of said firing opening, a fluid actuated piston, connections from said piston to said door for opening the same, a second fluid actuated piston, connections from said piston to said deflecting member for raising the same, and valvular means for simultaneously admitting fluid to said fluid actuated pistons.

8. In combination with a firebox having a firing opening, a fuel casing communicating with the lower portion of said firing opening, means for projecting fuel forwardly into said firebox in aerial paths, a firedoor frame embracing the upper portion of said firing opening, a firedoor for the upper portion of said firing opening mounted upon said frame, horizontal bearings formed with said frame, a hollow shaft mounted in said bearings, a hollow fuel deflecting member above the horizontal plane of the fuel projecting means and above the path of the projected fuel on said hollow shaft and arranged for movement about the axis of said shaft, said deflecting member being provided with a plurality of spaced openings and said hollow shaft being provided with a plurality of spaced openings communicating with said hollow deflecting member whereby a continuous current of air may pass through said hollow shaft and said deflecting member from without the firebox into the firebox, and means for simultaneously opening said door and raising said deflecting member, said means permitting the simultaneous closure of said firedoor and the return of said deflecting member to its lowered position upon its release from said opening and raising actions.

9. In combination with a firebox having a firing opening, a fuel casing communicating with the lower portion of said firing opening, means for projecting fuel forwardly into said firebox in aerial paths, a firedoor frame embracing the upper portion of said firing opening, a firedoor for the upper portion of said firing opening mounted upon said frame, horizontal bearings formed with said frame, a hollow shaft mounted in said bearings, a hollow fuel deflecting member above the horizontal plane of the fuel projecting means and above the path of the fuel, on said hollow shaft and arranged for movement in a vertical plane about the axis of said shaft, said deflecting member being provided with a plurality of spaced openings and said hollow shaft being provided with a plurality of spaced openings communicating with the interior of said hollow deflecting member whereby a current of air may pass through said hollow shaft and said deflecting member into the firebox, a fluid actuated piston, connections from said piston to said door for opening the same, a second fluid actuated piston, connections from said last named piston to said deflecting member for raising the same, and valvular means for admitting fluid to said fluid actuated pistons.
